ABSTRACT OF THE DISCLOSURE

This invention relates to a piston having a spiral gallery for cooling oil cast into its crown, and a transverse bridging member secured at its opposite ends to opposed shoulders within the piston, into which shoulders the opposite ends of the spiral gallery open. The bridging member has a central oil pick-up element co-operable with the small end of a connecting rod to pick up oil therefrom, the pick-up element communicating, via a gallery within the bridging member which extends from the pick-up element to one of the opposed shoulders, with the spiral oil gallery in the crown.

The present invention relates to pistons for internal combustion engines, and in particular to oil cooled pistons in which oil is fed to the piston crown via the small end of the piston connecting rod.

According to the present invention there is provided an oil cooled piston for an internal combustion engine wherein a separate transverse elongated bridging member spans the underside of the piston crown, and is secured at or adjacent its opposite ends to the piston adjacent the side wall thereof, the bridging member carrying a pick-up element arranged to resiliently and slidably engage the small end of a connecting rod when assembled to the piston, and being provided therein with a transverse gallery communicating with the pick-up element and with an oil gallery formed within the piston crown.

In order that the invention may be more readily understood, reference will now be made to the accompanying drawings, in which:

FIGURE 1 is a vertical section through a piston according to one embodiment of the invention, taken in the plane of the axis of the gudgeon pin bosses;

FIGURE 2 is a vertical section of the piston shown in FIGURE 1, taken in a plane normal to the axis of the gudgeon pin bosses;

FIGURE 3 is a transverse section on an enlarged scale of the bridging member taken on the line A—A of FIGURE 2;

FIGURE 4 is a fragmentary view on an enlarged scale of the bridging member taken in the direction of the arrow B in FIGURE 2; and

FIGURE 5 is a plan view of the crown of the piston shown in FIGURES 1 and 2, with the spiral oil gallery indicated in phantom lines.

Referring to the drawings, the piston is made as a one-piece casting, for example, from a non-ferrous metal such as an aluminium or magnesium alloy, or from a ferrous metal such as a steel, a malleable or cast iron, or spheroidal graphite iron. The piston comprises a crown 1, and a side wall including a ring carrier zone 2, a downwardly depending skirt 3, and integral gudgeon pin bosses 4. A top piston ring groove carrier insert may be cast into the zone 2 as shown, which, in the case of a non-ferrous piston casting, may be made of cast iron. Between the crown 1 and side wall, are cast a pair of integral shoul-

ders 5 disposed on opposite sides of the axis of the gudgeon pin bosses 4 as shown in FIGURE 2. A pair of blind tapped bores 6 are formed in each shoulder 5, and opening into the two shoulders between the pairs of bores 6 are ports 7 and 8 formed by the opposite ends of an oil gallery 9 which is cast into the crown 1 in the form of a continuous spiral cavity (FIGURE 5). For example, the radial inner end of this spiral gallery 9 may be connected to the port 7, which comprises the oil inlet port, whilst the outer end of the gallery 9 may be connected to the port 8 which comprises the oil outlet port.

An elongated transverse bridging member 10, for example a cast alloy beam of U-shape as shown in FIGURE 3, is secured across the shoulders 5 by means of bolts 11 threaded into the bores 6. The bridging member 10, at one end, is formed with a vertical passage 12 aligned and communicating with the port 7 and with an internal transversely extending gallery 13, which, in turn, communicates at its inner end with a vertical cylindrical cavity 14 in the central region of the bridging member 10. Within this cavity 14 there is slidably located an oil pick-up element or "slipper" 15 formed, for example, from steel, bronze, or a light alloy, which is normally urged by means of a spring 16 into engagement with bearing surface 17 formed on the upper surface of the small end of a piston connecting rod (not shown). The pick-up element 15 is provided with a vertical gallery 18 which communicates with the transverse gallery 13 via a cross bore 19.

The opposite end of the bridging member 10 is formed with an open ended passage or vent 20 aligned with the outlet port 8.

When in operation in an internal combustion engine, engine oil under pressure is fed up through internal passages in the connecting rod to lubricate the small end thereof, and some of this oil passes up through an opening in the bearing surface 17, through the pick-up element 15 which makes a sliding seal with the bearing surface, transversely through the bridging member 10, through and around the spiral gallery 9, and then back into the engine through the vent 20. During the passage of the oil through the gallery 9, the oil acts as a coolant by absorbing heat from the piston crown and also from the back of the upper piston ring groove.

By mounting the pick-up element 15 in a bridging member 10 which is simply bolted into the piston and which incorporates some of the oil ways of the cooling system, the manufacture of the oil-cooled piston, and also of the gudgeon pin used with the piston, is considerably simplified. Moreover, the pick-up element 15 may be used to convey oil directly into a cavity under the piston crown for cooling purposes, instead of, or in addition to, conveying oil through the transverse gallery 13. In the former case, the transverse gallery 13 may be blanked off or omitted, and the pick-up element 15 would have an axial opening in its upper end.

When providing this alternative or additional manner of cooling the underside of the piston crown, the bridging member 10 may be widened so as to form a "floor" to the cavity under the piston crown. Cooling oil fed through the pick-up element 15 will then be able to splash or shake up and down between this "floor" and the underside of the crown, in the well known manner of a cocktail shaker, so providing the maximum cooling effect before the oil escapes from the piston.

It will be understood that various modifications may be made without departing from the scope of the invention. For example, the bridging member may extend generally parallel to the axis of the gudgeon pin bosses instead of transverse thereto. Although a single spiral oil

gallery has been shown which is cast into the piston crown, the gallery may alternatively be circular or of any other desired configuration, and more than one gallery may be provided. The or each gallery may be cast into the crown using a soluble core technique, may be produced by casting a pipe or pipes into the crown, or may be produced in any other suitable way.

The or each gallery may be disposed solely in the region of the piston ring groove carrier zone, or in the region of the crown, or both, or may be omitted, the oil being fed into a cavity between the under surface of the crown and the bridging member.

We claim:

1. An oil cooled piston for an internal combustion engine, including a piston crown, a side wall depending from and integral with said piston crown, and gudgeon pin bosses integral with said side wall, an oil gallery comprising a continuous elongated tubular cavity within the crown, said gallery having an inlet port and an outlet port, a unitary detachable transverse elongated bridging member within the piston which spans and is spaced from the underside of the piston crown, and is secured by its opposite ends to internal mounting faces on the piston spaced apart on opposite sides of the piston axis and disposed adjacent the side wall, said bridging member engaging the piston only at said mounting faces, the bridging member carrying, intermediate its opposite ends, a depending pick-up element which is movable relative to the bridging member toward or away from the piston crown, means adapted normally to resiliently bias the pick-up element in a downward direction away from the piston crown, the pick-up element being provided therein with a downwardly opening oil gallery, communicating with an inlet end of a transverse oil gallery formed wholly within the bridging member and spaced from the underside of the piston crown, said transverse gallery having an outlet port at one of said opposite ends of the bridging member communicating with the inlet port of the oil gallery formed within the piston crown.

2. A piston according to claim 1, which comprises a light alloy casting, wherein said bridging member comprises an alloy casting in the form of a generally U section beam, extending generally normally to the gudgeon piston axis, having first and second upwardly directed faces disposed respectively at opposite ends of said beam, the outlet port of the transverse oil gallery within the beam opening into said first face, and an inlet port, which terminates the upper end of a downwardly extending open-ended vent in the beam, opening into said second face, said first and second upwardly directed faces mating respectively with first and second downwardly facing shoulders integral with the side wall on opposite sides of the crown and constituting said mounting faces, the beam being secured within the piston solely at the mating faces by bolts located in the region of said mating faces, the oil gallery within the crown comprising a continuous spiral oil gallery, the inlet port of which opens into said first shoulder in alignment with the inlet port of the transverse gallery in the beam, and the outlet port of which opens into said second shoulder in alignment with the inlet port of said vent.

3. A piston according to claim 2, wherein the beam is provided with a vertical cylindrical cavity in its central region communicating with the transverse gallery, within which cavity of the oil pick-up element is telescopically slidably mounted, and wherein said biasing means comprises a spring located within the cavity.

4. An oil cooled alloy piston for an internal com-

bustion engine, including a piston crown, a continuous elongated tubular oil gallery contained wholly within the crown, and having an inlet port at one end and an outlet port at its opposite end, a side wall depending from and integral with said crown, a pair of transversely spaced gudgeon pin bosses integral with said side wall and aligned with respect to a common transverse axis, first and second downwardly facing shoulders integral with and adjacent the side walls, spaced apart on opposite sides of the transverse axis of the gudgeon pin bosses, and disposed between the periphery of the underside of the crown and the gudgeon pin bosses, said inlet port opening into said first shoulder and said outlet port opening into said second shoulder, a separate transverse elongated bridging member disposed within the piston, located wholly externally of said continuous elongated tubular oil gallery, extending between said shoulders, spanning and spaced from the underside of the crown, said bridging member having, respectively, first and second upwardly directed faces at opposite transverse ends thereof, mating respectively with said first and second shoulders, said bridging member engaging the piston only at said shoulders, and being secured to the piston only in the region of said shoulders by bolts, said bridging member being provided with a vertical cylindrical cavity in its central region within which a depending oil pick-up element is telescopically slidably mounted, a compression spring disposed around the pick-up element within the cavity adapted normally to resiliently urge the pick-up element downwardly away from the crown, said element having a generally vertical downwardly opening oil passage therein communicating at its upper end with said cavity, a transverse oil gallery formed wholly within the bridging member communicating at one end with said cavity, extending from said cavity within the bridging member to a position adjacent said first upwardly directed face, and at its other end opening into said face in alignment with said inlet port in the first shoulder, a downwardly opening vent in the opposite end of the bridging member, opening into said second upwardly directed face in alignment with the outlet port in said second shoulder, whereby there is provided a flow path for cooling oil, said flow path comprising, in the direction of oil flow, the passage in the pick-up element, the cavity in the pick-up element, the transverse gallery in the bridging member, the inlet port, the continuous elongated tubular oil gallery in the crown, the outlet port, and the vent in the bridging member.
